S. P. THACHER

STONE GUARD FOR DUAL PNEUMATIC TIRES

Filed July 13, 1922

Inventor.
Sheldon P. Thacher

By his Attorney.
Ernest St. Omer

UNITED STATES PATENT OFFICE.

SHELDON P. THACHER, OF FREEHOLD, NEW JERSEY, ASSIGNOR TO MORGAN & WRIGHT, A CORPORATION OF MICHIGAN.

STONE GUARD FOR DUAL PNEUMATIC TIRES.

Application filed July 13, 1922. Serial No. 574,628.

To all whom it may concern:

Be it known that I, SHELDON P. THACHER, a citizen of the United States, residing at Freehold, county of Monmouth, and State 5 of New Jersey, have invented certain new and useful Improvements in Stone Guards for Dual Pneumatic Tires, of which the following is a full, clear, and exact description.

10 This invention relates to pneumatic tire casings and more particularly to a construction therefor adapted to exclude stones.

Frequently, a pair of pneumatic tires are mounted in juxtaposition on the wheel of a 15 vehicle, such as a truck, instead of a single large pneumatic. This is known as dual or twin mounting. One of the main objections to this practice is the tendency of the contiguous casings, as heretofore constructed, 20 to pick up stones which, becoming wedged between the casing, rapidly wear out the side walls and cause early failure of one or both tires.

An object of the present invention is to 25 prevent stones or other foreign matter from becoming lodged between the side walls of juxtaposed or dual casings and thereby prolong their life when mounted in pairs on a single wheel.

30 An embodiment of the invention is illustrated in the accompanying drawing in cross-section, showing conventionally a dual mounting.

In the drawings, a pair of casings 1 and 35 2 of the straight side-type equipped with wired margins 3 are shown mounted on disk-wheels 4 and 5, placed back to back and adapted to be supported on the axle spindle in a well-known manner. This mounting 40 may be employed or two separate rims may be mounted on a felloe band after the fashion of dual solids. The mounting of the casings, of course, forms no part of the present invention.

45 According to my invention, the side walls of the casings are molded with integral annular projections 6, preferably having substantially flat faces 7, extending approximately parallel to the plane of each casing and of greater width radially than thick transversely. These annular projections 50 are preferably located, as shown, at the

greatest bulge in the side walls and for a distance radially inward and outward there-of so as not to interfere with the ordinary 55 and usual deflection of a casing under load or to hamper access to the beaded margins of the casing when being mounted. The projections may be located on either or both of the side walls of each casing and may be 60 formed either by molding with the casings during the cure or by cementing a strip of durable rubber composition to one or both of their side walls after curing, the cement, if used, being preferably of the cold or 65 self-curing kind. A toughening agent, such as zinc oxide, may be incorporated in the composition before curing. After curing, the faces 7 may be indurated by brushing with bromine chlorine, or other halogen, in 70 dilute solution, about say 3%, such treatment imparting to the faces a leathery character.

It will be obvious that the form, shape 75 and location of the annular projections may be varied within wide limits. Particularly, their thickness may be proportioned so that the opposed faces 7 may be either slightly separated or in contact when the casings are either deflected or not deflected, the essential thing being to so locate them as to largely, if not entirely, exclude stones or other foreign matter of a character likely, 80 if lodged between the casings, to abrade and injure the side walls thereof.

It will therefore be understood that many 85 changes may be made in the construction without departure from the broad underlying principles of the invention and reference should be made to the accompanying 90 claims for an understanding of its scope.

Having thus described my invention, what I claim and desire to protect by Letters Patent is:

1. A pneumatic tire casing having integral annular projections on its side walls with substantially flat faces approximately parallel to the plane of the casing and of greater width radially than transversely of the casing, one of said annular projections 95 being adapted to co-operate with a similar projection on another casing so as to exclude stones.

2. Twin pneumatic tire casings for dual

mounting on motor vehicles having on their adjacent side walls annular projections adapted in opposition to exclude stones from lodgment between the casings.

5 3 Twin pneumatic tire casings for dual mounting on motor vehicles having on their adjacent side walls integral annular projec-

tions with opposed substantially flat faces adapted to contact with one another and exclude stones from lodgment therebetween

10

Signed at New York city, county of New York, and State of New York, this 12th day of July, 1922.

SHELDON P. THACHER.
